B. Hinkley,

Washing Machine,

Patented July 23, 1833

The following is a copy of the original manuscript of the sermon -
"A Discourse on the Work of the world by Benjamin Franklin himself of his
improvement in the Working-mechick."

Figs. 3, 4, 5, 6, of the drawing represent the machine, part of the description, adjacent to the box, into which the work, or part, and in which the machine is intended to operate. This may be three feet long one foot and a half wide and one foot deep, standing about two feet and a half high, at the centre of the side pieces of the box two grooves, filled with two small blocks, and separated at fig. 7, meet about one inch wide, and four inches deep, to let in the shaft of the screw cylinder, one end of which shaft is built up to form a crank, fig. 8. Fig. 9 of the drawing represents the main cylinder to be ten inches in diameter and eighteen inches long. Figs. D, E of the drawing represent two small cylinders, about four inches in diameter, and the same length of the main cylinder, one of them on each side of the main cylinder. The smaller cylinder will receive a quantity of water and running out from the side of the box about one-half an inch. On these spouts are placed a hook, fig. 10, one on each, a line, fig. 5, is fastened into a loop of one of these hooks and runs down the top of the side of these hooks and is drawn down by a weight. Fig. 6 sufficiently shows to keep the smaller cylinder pressed against the larger cylinder, so as to run in an angle of about sixty degrees, and to the same depth of the groove for the main cylinder, so prepared for the quantity of the smaller cylinder to work in. The box is filled with warm water as high as the bottom of the smaller cylinder, the clothes are laid on to the larger cylinder and the crank is turned, causing the motion backwards and forwards, so as to clean the clothes. The box may be covered with planks. What follows is a view of my own invention on the three cylinders being horizontal and the groove above, a view of the machine.
